United States Patent

Des. 236,786
Patented Sept. 16, 1975

236,786

TABLE

Dale D. Smith, Irvine, Calif., assignor to Samsonite Corporation, Denver, Colo.

Filed Jan. 25, 1974, Ser. No. 436,525

Term of patent 14 years

Int. Cl. D6—03

U.S. Cl. D6—177

FIG. 2.

FIG. 3.

FIG. 4.

FIG. 1 is a perspective view of a table, showing my design;

FIG. 2 is a lower plan view thereof;

FIG. 3 is a side elevational view thereof; and

FIG. 4 is an end elevational view.

The end opposite to that shown in FIG. 4 has the appearance of that shown in FIG. 4.

I claim:

The ornamental design for a table, as shown and described.
